UNITED STATES PATENT OFFICE.

ALFRED R. WILSON, OF DETROIT, MICHIGAN, ASSIGNOR TO HUTCHINS CAR ROOFING COMPANY, OF DETROIT, MICHIGAN, A CORPORATION OF MICHIGAN.

RUNNING-BOARD SADDLE.

Original application filed August 30, 1918, Serial No. 252,072. Divided and this application filed March 26, 1920. Serial No. 369,008.

To all whom it may concern:

Be it known that I, ALFRED R. WILSON, a citizen of the United States of America, residing at Detroit, in the county of Wayne 5 and State of Michigan, have invented certain new and useful Improvements in Running-Board Saddles, of which the following is a specification, reference being had therein to the accompanying drawings.

10 The invention relates to car roofs of that type in which the carlines extend above the roofing sheets and form the supports and weather-proofing caps therefor. One of the objects of the present invention is to obtain 15 a simple construction of running board saddle upon the carline, which saddle and carline may be assembled in the car roof as a unit. Other objects of the invention reside in the novel arrangements and combinations of parts as more fully hereinafter set forth. This application is a division of 20 my prior application, Serial No. 252,072, filed Aug. 30, 1918, for car roof.

In the drawings:

25 Figure 1 is a side elevation of a construction embodying my invention;
Figure 2 is a top plan view thereof;
Figure 3 is a cross section on the line 3—3 of Figure 2.
30 1 is a carline of T section having the web 2 and the head 3 formed by the lateral flanges 4 at the upper edge of the web, the carline being arched transversely of the car. 5 are relatively movable roofing sheets extending 35 from eaves to eaves of the car roof and provided at their side edges with upwardly-extending flanges 6 arranged below the lateral flanges of the carline.

40 For the purpose of weather proofing the car roof the lateral flanges 4 of the carline are curved downwardly and the upwardly-extending flanges 6 of the roofing sheets terminate in the lateral portions 7 in engagement with the lateral flanges of the carline. The upwardly extending flanges are spaced from the web 2 of the carline so that the roofing sheets are free to move relatively to the carline to a limited extent.

45 To more thoroughly weather proof the roof, the lateral flanges 4 of the carline terminate in the inwardly or downwardly-extending portions 8, the lower edges of which are near the main body portions of the roofing sheets. The roofing sheets als-

have the raised reinforcing corrugations 9 55 which extend longitudinally thereof and are located near the inwardly or downwardly-extending portions 8 of the carlines, whereby any moisture blown transversely of the sheets will tend to be deflected from the 60 space between the lower edges of the inwardly-extending portions and the sheets.

10 is a running board saddle preferably formed of pressed sheet metal and comprising the complementary portions 11 and 12, 65 each of which have the lower foot flanges 13 resting upon the lateral flanges 4 of the head 3 of the carline and secured thereto by suitable means, such as by spot welding. The edges of the foot flanges extend 70 down the inwardly or downwardly-extending portions 8 of the carlines to embrace the latter, whereby a stronger construction is made possible. The complementary portions 11 and 12 have near the ends of their 75 webs the abutting inwardly-extending embossed portions 14 which are suitably connected, as by the rivets 15, thereby making a rigid construction. The complementary sections also have the laterally-extending 80 flanges 16 at the upper edges of their webs upon which the running boards 17 are mounted. These running boards are secured to the laterally-extending flanges by means of the bolts 18 passing through the 85 running boards and flanges.

From the above description it will be readily seen that I have provided a simple construction of running board saddle adapted to be used upon carlines of T section. The 90 complementary sections of these running board saddles can be easily manufactured and assembled upon the carlines. Furthermore, the construction is such that the saddles can be secured upon the carlines before 95 the latter are assembled in the car roof.

What I claim as my invention is:

1. In a car roof, the combination with a carline having a flange at its upper edge, of a running board saddle secured to said 100 flange and comprising complementary portions secured to each other and also secured individually to said flange.

2. In a car roof, the combination with a T-carline, of a running board saddle comprising complementary stampings secured to the head of the T.

3. In a car roof, the combination with a

T-carline, of a running board saddle embracing the head of the T, comprising spaced complementary sections each secured to said head and having inwardly extending embossed portions and laterally extending flanges at their upper edges for engagement with the running boards.

4. In a car roof, a running board saddle comprising complementary portions having adjacent webs secured to each other, and laterally-extending flanges at the upper and lower edges of the webs, the flanges at the lower edges being adapted to be secured to a transverse roof member.

15 5. In a car roof, the combination with a carline having a flange at its upper edge, of

a running board saddle comprising complementary sections individually secured to said flange and having laterally extending flanges at their upper edges for engagement with the running boards. 20

6. In a car roof, the combination with a carline having a flange at its upper edge, of a running board saddle comprising complementary sections each secured to said flange 25 and together embracing the same, said sections having adjacent webs secured to each other and laterally extending flanges at their upper edges for engagement with the running boards. 30

In testimony whereof I affix my signature.

ALFRED R. WILSON.
